UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

SIDE FRAME.

Application filed August 12, 1925, Serial No. 49,804. Renewed December 9, 1927.

This invention relates to side frames for railway car trucks, and more particularly to the strengthening of such side frames adjacent the ends thereof.

5 The principal object of my invention, generally considered, is the reinforcement of the compression and tension members of a cast side frame adjacent the junction of said members as well as increasing the strength 10 of the union between journal boxes and the corresponding ends of the frame.

An object of my invention is the improvement 15 in the design of the tension member of cast side frames for railway car trucks and its union with integral journal boxes at the ends thereof by curving the web of said tension member, which is preferably channel shaped in cross section, downwardly to unite 20 with the side wall of the adjacent journal box and flaring the flanges of said tension member to follow the diverted web portion and thereby increase the area of the side walls 25 of the frame adjacent the journal boxes, said side walls being reinforced and the connection between the tension member and corresponding journal box increased by triangular web 30 portions extending from below the beginning of the curved portion of the tension member web to approximately the upper inner corner of the corresponding journal box.

Another object of my invention is the improvement in design of side frames for railway car trucks in which the compression and tension members are generally channel shaped 35 in cross section and an integral journal box is provided at each end of the frame, the web of the tension member preferably extending generally in the direction of the upper inner corner of the adjacent journal box, by curving the web downwardly adjacent said journal box to meet the side wall thereof, extending the tension member flanges to follow the web portion, and reinforcing said flanges, the tension member, and the connection between 40 it and the journal box by web or rib portions extending from below the beginning of the curved portion of the tension member web along the flanges thereof to approximately 45 the upper inner corner of said journal box where it merges therewith.

A further object of my invention is the improvement in the design of the tension member in cast side frames for railway car trucks, said side frames having a tension

member generally channel shaped in cross section with a lower web and upstanding flanges therefrom and integral journal boxes at the ends of the frame, said web being curved downwardly and meeting the side wall of the adjacent journal box, the width 60 of the tension member flanges being reduced or tapered to a minimum adjacent the beginning of the curved portion of the web thereof and increasing both ways therefrom.

A still further object of my invention is 65 the provision of a side frame for railway car trucks, said frame having compression and tension members generally channel shaped in cross section, the flanges of each member extending towards those of the other and merging therewith, the edges of said flanges defining the outer portion of an opening between said members, said edges being reinforced by beading therealong which is formed of maximum depth or strength for a portion 70 adjacent the junction between said members, gradually decreased both ways therefrom to a minimum and then continued along said members at a substantially uniform depth or 75 strength.

80 Other objects and advantages of the invention relating to the particular arrangement and combination of parts will become apparent as the description proceeds.

Referring to the drawing illustrating my 85 invention, the scope whereof is pointed out in the claims:

Figure 1 is a fragmentary side elevation of 90 one end of a side frame for railway car trucks embodying my invention.

Figure 2 is a fragmentary plan view of the 95 side frame as illustrated in Figure 1.

Figure 3 is a cross sectional view on the line 3—3 of Figure 1 and looking in the direction of the arrows.

Referring to the drawing more particularly, like parts being designated by like reference characters, there is illustrated one end of a side frame 1 for railway car trucks, the remainder of said frame, being of well known 100 construction and not involving features of my present invention, not being illustrated.

105 In the embodiment shown, the frame comprises a compression member 2, a tension member 3, the ends of said members being integrally united at 4, as is usual in such construction, and preferably formed with a journal box 5 adjacent the junction between the

compression and tension members at each end of the frame.

As will be understood, the side frame is symmetrical and may be formed, as is usual, with bolster column or strut portions spacing intermediate portions of the compression and tension members and defining a window opening therebetween. Between the compression and tension members and on either side of the bolster column or strut portions are also formed the usual triangular openings 6. Certain of the aforementioned details, which are not part of my invention except as will be hereinafter pointed out, may be of any well known or preferred form.

The compression member 2 and tension member 3 preferably extend substantially the full length of the side frame, as will be understood, and at each end of said frame there is provided a journal box 5 preferably integral therewith. Said compression and tension members, in the present embodiment, are formed generally U-shaped in cross-section with a main web portion 7 and flange portions 8 on opposite sides of the web portion, said flange portions, in the embodiment shown, extending inwardly or towards each other and merging at the junctions between the compression and tension members to form flat side wall portions which are extended over and unite with the roofs 9 of the journal boxes. The free edges of the flange portions are preferably beaded, thickened or provided with a rib 10 which extends around the corner of the triangular opening 6 from the compression member 2 to the tension member 3.

According to my invention said rib is specially constructed so as to increase the strength of the frame at critical portions thereof, that is, the rib 10 although for the greater portion of its length is generally uniform in height or strength, is tapered or increased in height or strength along the compression member 2 from a point above the junction of the compression and tension member portions to approximately said junction which is, in the present instance, slightly above the level of the journal box roof 9. From there it is continued at maximum height or strength downwardly along the edges of the tension member flanges to a point, indicated by 11, somewhat below the level of the journal box roof. From the point 11 the depth or strength of the beading 10 around the triangular opening 6 is decreased gradually to a uniform minimum and continued around said triangular opening as such.

The point 11, where the beading 10 starts to taper or decrease downwardly, is preferably slightly above where the web 7 of the tension member 3 curves downwardly from a straight line. It will be noted that the plane of the main portion of said web 7, if continued, would meet the journal box at approximately the upper inner corner thereof, but in order

to rigidify the construction, said web is curved downwardly away from the plane of the main portion, and extends outwardly to meet the inner side wall 12 of the adjacent journal box at 13.

It will be apparent from considering Figure 1, particularly, that the flanges 8 of the tension member 3 are flared to correspond with the downward bending or curving of the web 7, thereby forming relatively large flat side walls adjacent each journal box. These side walls are preferably strengthened or reinforced and the union between the frame and journal boxes rigidified by triangular web or rib portions 14 extending from below the beginning of the curved portion of the web 7, preferably in line with the straight portion of said web, and continued to the adjacent journal box, preferably uniting therewith at approximately the upper inner corner, as illustrated. These webs or flanges 14, as will be apparent, not only increase the strength of the union between the journal boxes and frame, but form a valuable reinforcement to the tension member at a particularly critical portion thereof.

The tension member 3 instead of being formed with flanges 8 decreasing in width, or converging toward the plane of the straight part of the web, from their lower inner portions to their upper outer portions for approximately the full length thereof, is preferably so constructed that said flanges reach a minimum in width at approximately the point where the web portion 7 curves adjacent the point 11 and from said point are increased both ways.

By virtue of the aforescribed construction the strength of the side frame is greatly improved because the reinforcing flanges 14 and the increased portions of the beading 10 are applied at critical sections of the frame. The increasing of the width of the tension member flanges above the point where the web 7 diverges from its normally straight direction also results in improving the strength at the same critical portion of the frame. That is, it will be seen that the portion of the tension member adjacent its outer or upper ends, where it is liable to break in service, is increased or reinforced in three ways; first, by the triangular web portions 14, second, by increasing the width of the flanges 8, and third, by increasing the height, width or strength of the beading 10 at this point. This increase in strength of the tension member not only affects that member itself but also the connection between the journal boxes and the frame, as will be understood. The web 7 of the compression member 2 is preferably curved downwardly at its end and merges with the outer wall 15 of the adjacent journal box, the central portion of said web, however, being preferably omitted as indicated at 16, in accordance with the usual practice.

Having thus described the invention, I claim:

1. A truck side frame comprising a compression member, a tension member, said members converging at their ends and united together, a journal box integrally united to each end of the frame, said tension member being channel shape in cross section, with the web of the channel sloping generally in the direction of the upper inner corner of the adjacent journal box, curving downward adjacent said journal box and united with the inner side wall thereof, the flanges thereof being correspondingly widened, joined with the journal box wall and reinforced with triangular web portions extending from below the beginning of the curved portion of the web, outwardly and upwardly, and joined with the journal box adjacent the upper inner corner. 70
2. A truck side frame comprising a compression member, a tension member, said members converging at their ends and united together, a journal box integrally united to each end of the frame, said tension member being channel shape in cross section, with a lower web portion and upstanding flanges on either side thereof, the end portions of said tension member sloping outwardly and upwardly with the web extending generally in the direction of the upper inner corner of the adjacent journal box, said web being diverted adjacent the journal box so that it merges therewith a substantial distance below said corner, the flanges being correspondingly widened and merging with the journal box, and reinforcing webs extending from below the place of divergence of the web along the flanges of the tension member and merging with the journal box. 80
3. A truck side frame comprising a compression member, a tension member, said members converging at their ends and united together, a journal box integrally united to each end of the frame, said tension member being channel shape in cross section with side flanges and a bottom web, and having end sections sloping outwardly and upwardly, the web of each section extending in about the direction of the upper inner corner of the adjacent journal box, said web being curved downwardly adjacent said journal box and extended to meet the side wall thereof, the flanges following the path of the web to form relatively large flat side walls, and reinforcing ribs extending along said walls from below the beginning of the curved web portion to the journal box. 90
4. A truck side frame comprising channel shaped compression and tension members, said members having web portions, and flanges merging at their ends and united together, a journal box at each end of the frame, the web of the tension member sloping generally straight in the direction of the upper inner corner of the adjacent journal box to near said corner, where it curves downwardly to connect with the side wall of the box, the flanges of said tension member flaring outwardly at their ends to follow the diverted web and increase the width of the side walls formed by the compression and tension member flanges, and triangular web portions extending along said side walls, in line with the straight portion of the tension member web, from below the beginning of the curved portion thereof to the adjacent journal box. 95
5. A truck side frame comprising a compression member, a tension member, said members converging at their ends and united together, a journal box integrally united to each end of the frame, said tension member being channel shape in cross section, with the web of the channel sloping generally in the direction of the upper inner corner of the adjacent journal box, curving downward adjacent said journal box and united with the inner side wall thereof, the flanges thereof being correspondingly widened, joined with the journal box wall and reinforced with triangular web portions extending from below the beginning of the curved portion of the web, outwardly and upwardly, and joined with the journal box adjacent the upper inner corner, said flanges decreasing in width to approximately the beginning of the curved web and from there increasing, above the plane of the straight part of the web, to the union with the compression member. 100
6. A truck side frame comprising channel shaped compression and tension members, said members having web portions and flanges merging at their ends and united together, a journal box at each end of the frame, the web of the tension member sloping generally straight in the direction of the upper inner corner of the adjacent journal box to near said corner, where it curves downwardly to connect with the side wall of the box, the flanges of said tension member flaring outwardly at their ends to follow the diverted web and increase the width of the side walls formed by the compression and tension member flanges, and triangular web portions extending along said side walls, in line with the straight portion of the tension member web, from below the beginning of the curved portion thereof to the adjacent journal box, the tension member flanges decreasing in width to approximately the beginning of the curved web and from there increasing, above the plane of the straight part of the web, to the union with the compression member. 105
7. A truck side frame comprising a compression member, a tension member, said members converging at their ends and united together, a journal box integrally united to each end of the frame, said tension member being channel shape in cross section, with the web of the channel sloping generally in the 110
8. A truck side frame comprising a compression member, a tension member, said members converging at their ends and united together, a journal box integrally united to each end of the frame, said tension member being channel shape in cross section, with the web of the channel sloping generally in the 115
9. A truck side frame comprising a compression member, a tension member, said members converging at their ends and united together, a journal box integrally united to each end of the frame, said tension member being channel shape in cross section, with the web of the channel sloping generally in the 120
10. A truck side frame comprising a compression member, a tension member, said members converging at their ends and united together, a journal box integrally united to each end of the frame, said tension member being channel shape in cross section, with the web of the channel sloping generally in the 125

direction of the upper part of the adjacent journal box, the end portion, however, curving downwardly adjacent said box and joining therewith, the flanges of said tension member being of minimum width at approximately the beginning of the curved portion of the web and increasing in width, above the plane of the straight part of the web, both ways therefrom.

19. 8. A truck side frame comprising channel shaped compression and tension members, said members having web portions and flanges merging at their ends and united together, a journal box at each end of the frame, the web of the tension member sloping generally straight in the direction of the upper inner corner of the adjacent journal box to near said corner, where it curves downwardly to connect with the side wall of the box, the flanges of said tension member flaring outwardly at their ends to follow the diverted web and increase the width of the side walls formed by the compression and tension member flanges, triangular web portions extending along said side walls, in line with the straight portion of the tension member web, from below the beginning of the curved portion thereof to the adjacent journal box, said flanges being reinforced along their free edges by beading which extends at a maximum height adjacent the junction between compression and tension member flanges and decreases both ways therefrom.

9. A truck side frame comprising channel shaped compression and tension members, said members having web portions and flanges merging at their ends and united together, a journal box at each end of the frame, the web of the tension member sloping generally straight in the direction of the upper inner corner of the adjacent journal box to near said corner, where it curves downwardly to connect with the side wall of the box, the flanges of said tension member flaring outwardly at their ends to follow the diverted web and increase the width of the side walls formed by the compression and tension member flanges, triangular web portions extending along said side walls, in line with the straight portion of the tension member web, from below the beginning of the curved portion thereof to the adjacent journal box, said flanges being beaded along their free edges, said beading being strongest at a section from a point slightly above the level of the journal box roof downwardly to slightly above where the web of the tension member begins to curve and gradually decreasing from both ends of said section to a minimum and continued along said members.

10. A truck side frame comprising compression and tension members merging at their ends, said members being generally channel shape in cross section with web portions and flanges on either side thereof, the

flanges of one member extending toward those of the other and the flange edges curved to unite and define the corner of an opening between said members, said edges being reinforced by beading therealong and said beading being gradually increased transversely and extended at a maximum for a distance adjacent said corner.

11. A truck side frame comprising compression and tension members merging at 75 their ends, said members being generally channel shape in cross section with web portions and flanges on either side thereof, the flanges of one member extending toward those of the other and the flange edges 80 curved to unite and define the corner of an opening between said members, said edges being reinforced by ribbing along the same, said ribbing being of uniform height along 85 the compression member to adjacent the junction with the tension member from where it is gradually increased to a maximum at said junction, and extended uniformly for a distance along the tension member and then decreased gradually to its original height.

12. A truck side frame comprising compression and tension members, said members being formed with upright portions joined with transversely disposed portions, the upright portions of one member extending towards those of the other with their adjacent edges curved to unite and define a portion of an opening between said members, said edges being reinforced by transversely disposed 95 portions which are gradually increased in a transverse direction and extended at a maximum adjacent the junction between said members.

13. A truck side frame comprising compression and tension members, said members being formed with upright portions joined with transversely disposed portions, the upright portions of one member extending toward those of the other with portions of their 105 adjacent edges curved to unite and define an opening between said members, said edges being reinforced by transversely disposed portions which are gradually varied in 110 strength in a transverse direction to efficiently reinforce said members.

14. A truck side frame comprising compression and tension members, said members being formed with flanges joined by webs, the flanges of one member extending towards 120 those of the other with their adjacent edges curved to unite and define a portion of an opening between said members, said edges being reinforced by transversely disposed portions of non uniform depth.

15. A truck side frame comprising a compression member, a tension member, said members converging at their ends and united together, a journal box integrally united to each end of the frame, said tension member 130

- being channel shape in cross section, with the web of the channel sloping generally in the direction of the upper inner corner of the adjacent journal box, curving downward adjacent said journal box and united with the inner side wall thereof, the flanges thereof being correspondingly widened, joined with the journal box wall and reinforced with triangular web portions extending outwardly and joined with the journal box adjacent the upper inner corner.
16. A truck side frame comprising a compression member, a tension member, said members converging at their ends and united together, a journal box integrally united to each end of the frame, said tension member

being channel shape in cross section, with a lower web portion and upstanding flanges on either side thereof, the end portions of said tension member sloping outwardly and upwardly with the web extending generally in the direction of the upper inner corner of the adjacent journal box, said web being diverted adjacent the journal box so that it merges therewith a substantial distance below said corner, the flanges being correspondingly widened and merging with the journal box, and reinforcing webs extending along the flanges of the tension member and merging with the journal box.

In testimony whereof I affix my signature.
